[57] CLAIM

The ornamental design for a combined front panel and
bumper unit exterior surface, as shown.

DESCRIPTION

FIG. 1 is a front side perspective view of the combined
front panel and bumper unit exterior surface for a motor
home showing the new design;

FIG. 2 is a front elevational view thereof;

FIG. 3 is a left side elevational view thereof;

FIG. 4 is a right side elevational view thereof; and

FIG. 5 is a top plan view thereof.

FIG. 2

FIG. 1
